CAPPING HEAD

Josef Einar Jonsson, Linkoping, Sweden

Application October 7, 1941; Serial No. 413,941
In Sweden October 2, 1940

3 Claims.

(Cl. 226—85)

The present invention relates to a bottle capping device, and particularly to a bottle capping device of the type in which a pressure piston displaceable in a capping head cooperates with a suitable capping tool such as a rubber ring adapted to press the skirt of a bottle cap placed on the mouth of a bottle tightly against the peripheral wall of the bottle neck. In devices of this kind, the pressure piston is actuated by the movement of the capping head in a capping head carrier.

One object of the invention is to provide a capping device of the type set forth in which the radial pressure exerted by the capping tool upon the bottle neck is rapidly increased to a certain value during the initial portion of the relative movement between the capping head and its carrier, whereas after this proper capping pressure has been reached, no further increase in radial pressure is effected regardless of the length of the subsequent relative movement between the capping head and its carrier.

Another object of the invention is to provide a capping device of the type mentioned in which a single spring controls the relative displacement between the capping head and its carrier and also the relative displacement between the pressure piston and the capping head.

Still another object of the invention is to provide a capping device which permits capping of bottles, the heights of which differ within certain rather wide limits without any readjustment of the mechanism and without change in the length of the stroke carried out by the carrier of the capping head or the bottle support.

A still further object of the invention is to provide a capping device, in which all parts, after each capping operation, are returned easily and smoothly to their starting positions so that capping operations can be carried out in rapid succession.

These objects are accomplished by the arrangement and combination of elements set forth in the following detailed description, defined in the appended claims and illustratively exemplified in the accompanying drawings in which

Fig. 1 is a vertical section of a capping device according to the invention at the beginning of a capping operation.

Fig. 2 is a sectional view of a detail taken on line 2—2 of Fig. 1, and

Fig. 3 is a vertical section similar to that of Fig. 1 showing the position of the various parts at the completion of a capping stroke.

In the drawings, the reference numeral 1 denotes a support element vertically reciprocable through a predetermined distance. A tubular capping head carrier 3 is rigidly mounted on the support 1 by means of a bracket 2. The capping head itself consists of an upper portion 4, slid-

able in the carrier 3, and a lower portion 6. The latter is provided with a channel 6a for the introduction of the bottle caps 28 and a channel 6b communicating with a source of suction and also, through a narrow slot 6c, with the channel 6a. Each cap is moved by the suction coming from the channel 6b through the channel 6a to its proper center position in the capping head portion 6 and is stopped in this position by a shoulder formed on the latter. The lower head portion 6 is screwed into the upper portion 4 and is provided, on its underside, with a tapering opening 32 adapted to receive the top of a bottle. A rubber ring 7 is seated on an annular flange formed in said portion 6 above the opening 32. A pressure piston 8, slideable in an axial recess of the upper portion 4 of the capping head, bears with its lower rim against the ring 7 so that, upon downward displacement of the piston 8 relative to the capping head portion 6, the rubber ring 7 is axially compressed and caused to spread radially inward so as to press the skirt of a bottle cap 28 seated on top of a bottle 29 against the peripheral wall of the bottle neck. The pressure piston 8 surrounds a spring actuated counterpressure piston 9 which serves to retain the cap 28 in position on the mouth of the bottle 29 during the initial stages of the capping operation. A seating surface formed in the piston 8 rests upon the rim of the bottle mouth when the counterpressure piston 9 has reached its uppermost position. (See Fig. 3.)

One end of a lever 10 is pivoted at 11 in the upper portion 4 of the capping head above the upper end of the pressure piston 8. A convex portion 10a of the lever 10 rests upon and cooperates with the upper surface of the piston 8. The other end of the lever 10 is pivoted at 12 to the lower end of a vertical rod 13. A compression spring 14 surrounds the rod 13 and is seated with its opposite ends against two flanged sleeves 15, 16 slidable on the rod 13. The upper sleeve 15 presses against one end of a balance lever 19. The lower sleeve 16 rests on adjustable nuts 17 by means of which the pressure of the spring may be regulated. The rod 13 extends through a cross piece 21 fixed to and forming an integral part of the capping head carrier 3. Nuts 18 on the upper end of the rod 13 limits the downward movement of the latter relative to the cross piece 21 and carrier 3. A protective casing 33 for the rod 13 and spring 14 is detachably suspended from the cross-piece 21.

The upper end of the head portion 4 is provided with two ears 30 between which a slightly tapered finger 22 is pivotally mounted on a pivot pin 23. The tip of the finger 22 is disposed, in the position of the device shown in Fig. 1, between two rollers on pins 24 and 25, the pin 24 being mounted in the carrier 3, while the pin

25 is supported in a plunger 26 which is slideable in the carrier 3. Another roller carried by the plunger 26 on a pin 27 above the pin 25 supports the inner end of the balance lever 19, the latter being pivoted on a pin 20 provided in the cross piece 21.

The capping device according to the invention operates as follows:

The support 1 lowers the capping head carrier 3 with the capping head 4/6 towards the bottle 29 on the table 31 so that the neck of the bottle enters the opening 32 in the lower head portion 6, where it comes in contact with the cap 28 previously brought into the proper position as described above. The cap 28 in turn seats against the counterpressure piston 9 which is then stopped by the top of the bottle. The head 4/6 and its carrier continue their downward movement until the seating surface of the pressure piston 8 strikes against the cap 28 and the bottle top and both, the cap and the bottle top, are surrounded by the rubber ring 7. Now, the downward displacement of the head 4/6 is ended and, upon further downward movement of the support 1 and carrier 3, the capping mechanism is operated. During the first part of the downward movement of the carrier 3 relative to the head 4, the lever 10 does not turn about its pivot 11, but the spring 14 is compressed due to the downward movement of the pivot pin 20 relative to the pivot pin 12 and the nuts 18 are lifted off the cross-piece 21. Simultaneously, the tip of finger 22 penetrates between the rollers on pins 24 and 25, thus effecting a small upward displacement of the plunger 26 in the carrier 3 to the position shown in Fig. 3. This causes the balance lever 19 to turn to the position shown in Fig. 3 and increases the load on spring 14 to such an extent that it becomes equal to the resistance of the rubber ring 7 against compression. During the next part of the downward displacement of the carrier 3, the lever 19, pin 20, rod 13, and spring 14 move down as a rigid unit and cause the lever 10 to swing about its pivot axis 11 from the position shown in Fig. 1 to that shown in Fig. 3. Since the convex portion 10a of the lever 10 which rests on the pressure piston 8 and, through the latter, on the top of the bottle, cannot descend any further, the downward movement of the pivot pin 12 causes the lever 10 to swing about its convex surface 10a as a fixed fulcrum and to impart a slight rise to the capping head 4/6 in which the pivot pin 11 is mounted. The lifting of the head portion 6 relative to the pressure piston 8 causes an axial compression of the rubber ring 7 between the pressure piston 8 and the flange of the capping head portion 6 on which the ring 7 is seated. Since the practically incompressible rubber has no other escape than radially inward, the material of the ring 7 is spread in this direction, and the axial pressure is thus transformed into radial pressure which acts to force the skirt of the cap 28 against the periphery of the bottle neck, as shown in Fig. 3. This movement continues until the lever 10 has reached the position shown in Fig. 3, in which position it is in contact with the lower wall of the recess in the head 4 and prevented from any further tilting movement relative to the head. Subsequent downward displacement of the carrier 3 causes a further compression of the spring 14 due to the downward movement of the pin 20 relative to the, now fixed, pivot pin 12, but there is prac-

tically no additional change in the position of the balance lever 19, because the taper of finger 22 is very flat and just sufficient to insure a smooth withdrawal of the finger 22 from between the rollers 24, 25 when the carrier 3 is returned to its starting position.

Thus, regardless of the height of the bottle and regardless of the fact that the total downward stroke of the carrier has always the same length, the radial capping pressure exerted by the ring 7 will always reach the same magnitude when the carrier has carried out a movement of a predetermined length after the cap has been seated on the bottle, but regardless of the extent of the subsequent downward movement of the carrier, which is greater in the case of a tall bottle and less in the case of a small bottle, the radial pressure can never exceed this predetermined magnitude and the further increase in the spring load, which is kept comparatively small owing to the shape of the finger 22, is taken up uniformly by the rim of the bottle mouth and the cap seated thereon in a substantially axial direction.

I claim:

1. A bottle capping device including a bottle support and a capping head carrier vertically reciprocable relative to each other through a predetermined distance, a capping head vertically slideable in said carrier, a capping tool seated in said capping head, a pressure piston vertically displaceable in said capping head for actuating said capping tool, a lower lever pivoted in said head for limited rocking movement relative thereto and having a portion cooperating with said pressure piston, an upper lever pivoted in said carrier, means to transmit to said upper lever upon downward displacement of said carrier relative to said capping head a rocking motion which is substantially the same regardless of the magnitude of said displacement, and spring means provided between said upper and lower levers eccentrically of the axis of said pressure piston to actuate the latter and said capping tool with a predetermined spring pressure at a certain point of each displacement of said carrier relative to said capping head.

2. A bottle capping device, as claimed in claim 1 including a guide rod pivoted to the outer end of said lower lever, a cross piece on said carrier above said upper lever, the upper end of said guide rod passing through and being guided in said cross piece, an upper flanged sleeve slideable on said guide rod and resting with its upper surface against the outer end of said upper lever, a lower flanged sleeve slideable on said guide rod, a nut on said guide rod to permit vertical adjustment of said lower sleeve thereon, said spring surrounding said guide rod and being supported with its opposite ends on said two flanged sleeves, respectively.

3. A bottle capping device, as claimed in claim 1 in which said means to transmit rocking motion to said upper lever comprises a plunger vertically slideable in said carrier and supporting the inner end of said upper lever, a roller mounted on said plunger, and a slightly tapered finger pivoted on the upper end of said capping head and adapted to penetrate between said two rollers when said carrier is displaced downwardly with respect to said capping head thereby imparting to said upper lever a rocking movement which is substantially the same regardless of the amount of such relative displacement.

JOSEF EINAR JONSSON.
